RAY E. BELLONBY, OF CINCINNATI, OHIO

EXTENSION TABLE

Application filed March 26, 1927. Serial No. 178,729.

My invention relates to extension tables such as dining room tables in which additional table boards may be added by opening up the sides of the table and inserting the desired number of additional boards.

It is the object of my invention to provide a mechanism in combination with a table which may be readily actuated by the woman in the home which will avoid the necessity of pulling first on one end of the table and then on the other and incurring the physical strain incident to opening up a table not provided with mechanical extending means. It is further my object to construct a table so that it will readily accommodate itself to a mechanical extending device.

The above and other objects in connection with novel means for guiding the sliding members of the table, I accomplish by that certain arrangement and combination of parts of which I have illustrated a preferred embodiment.

Referring to the drawings:

Figure 1 is a perspective view of an extension table in open position so that the actuating mechanism may be seen.

Figure 2 is a vertical section taken along the lines 2—2 in Figure 1, looking in the direction of the arrows.

Figure 2^a is a vertical section taken along the lines 2^a—2^a in Figure 1, looking in the direction of the arrows.

Figure 3 is a vertical section taken along the lines 3—3 in Figure 1.

Figure 4 is a vertical section taken along the lines 4—4 in Figure 1.

Figure 5 shows a diagrammatic side elevation of another modification of the type of extending mechanism shown in the other figures.

The end pieces of the table top are indicated at 1, 2, having the downwardly extending side bars 3, 4. The table top portions 1 and 2 are supported by lengthwise extending rails such as are indicated at 5—5, and the table top ends consisting of the parts 1, 2, are slidably mounted on the rails being held thereto by the extending mechanism which will be hereinafter described. Legs 6—6 are mounted on cross braces 7—7 widthways

across under the rails 5—5. The legs may also be mounted directly on the cross braces 5—5. Supports 7^a—7^a may also be extended widthwise of the table at the ends of the rails 5—5 for increasing the rigidity of the assembly and supporting the pulleys. The supporting structure for the table top in the illustration shown is, therefore, immovable. The top parts are slidable to expose such an open area between them that a desired number of boards may be inserted. For mechanically extending the table top I have provided mechanism as follows: Extending across the table laterally, preferably at the center thereof, I have mounted in journals 8—8 the spindle shaft 9 which preferably has a central drum portion 10. Ropes or cables 11—11 may be extended from fasteners 11^a—11^a near the inner edges of the parts 1 and 2 and then through pulleys 12—12^a, 13—13^a mounted on the supports 7^a—7^a respectively, after which they are wrapped around the drum 10 to which they may be secured. The specific arrangement herein-after described is not essential, it being my purpose in the particular construction shown to provide a drum the turning of which will cause the ends of the table top to move equally to and from the center of the table.

Considering first Figure 2, a cable 11 is attached to a fastener 11^a secured close to the inner edge of the part 1. The cable is then passed to the left around the pulley 12, then with one or more wraps around the drum 10 passing from left to right clockwise around the drum 10. The cable is then passed under and around the pulley 12^a and back to the fastener, from which the cable was originally extended.

Considering now Figure 2^a, a cable is attached to a fastener 11^a close to the inner edge of the part 2, then to the left around the pulley 13. After being passed around pulley 13 the cable is passed around the drum 10 counter-clockwise from left to right. Next the cable is passed under and around the pulley 13^a and then back to the original fastener.

The shaft 9 may have a portion such as is indicated at 14 having a pin extending radially therefrom which is adapted to be engaged

by a detachable turning handle 15 which I ordinarily provide for actuating the extending mechanism. It will be apparent that the shaft 9 may be shaped to engage a handle on either or both sides as shown in Figures 1 and 4. The table end portions 1 and 2 have secured to their lower surfaces track portions such as are indicated at 16-17 respectively. The track portions may be kept in alignment on the rails 5-5 by means of screws 18 secured in the central zone of the upper surface of the rails 5-5. The screws have wide heads which act as guides for the tracks which being secured to the table top ends slide with the extension of the table top ends. In order to provide bearings for the tracks I have further found it advisable to insert rollers 19 within sockets on the sides and tops of the rails 5-5.

26. The extending mechanism which I have disclosed may be the subject of many mechanical modifications. For example, in Figure 5 I have shown a different arrangement in which the central spindle 9 has a pinion 19^a and each one of the table ends 1 and 2 have racks 20 attached thereto which engage the pinion, one above the center thereof and one below. It will be obvious that when the spindle is turned the racks will cause the movement of the table ends apart or together in accordance with the direction in which the spindle is turned. In combination with the rack and pinion mechanism the track and guide arrangement illustrated in Figures 1, 3, and 4 will preferably be used. I find the use of L-shaped tracks as guiding means are thus provided which will tend to prevent the sliding mechanism from getting out of order.

26. Having thus described my invention, what I claim as new and desire to secure by Letters Patent, is:-

1. In an extension table, a base, top boards 27. slidable over said base toward and away from each other, parallel rails fixed to said base and extending in the direction of movement of said top boards, guides upon said top boards, said guides comprising an angle member one face of which rides upon the top of said rail and the other face of which extends along the side of said rail, said guides arranged in pairs whereby the top faces of two guides will overlie a single rail, the side faces thereof lying on either side of said rail to prevent lateral movement of said top boards, and rollers on the top of said rails to form a bearing for said top faces of the guides, and rollers on the sides of said rails to provide a bearing for the side faces of said guides.

2. In an extension table, a base, top boards 28. slidable over said base toward and away from each other, parallel rails fixed to said base and extending in the direction of movement of said top boards, a guide upon each of said

top boards for each of said rails, said guides comprising an angle member one face of which rides upon the top of said rail and the other face of which extends along the side of said rail, said guides arranged in pairs whereby the top faces of two guides will overlie a single rail, the side faces thereof lying on either side of said rail to prevent lateral movement of said top boards, and rollers on the top of said rails to form a bearing for said top faces of the guides, and rollers on the sides of said rails to provide a bearing for the side faces of said guides. 70

3. In an extension table, a base, top boards 80. slidable over said base toward and away from each other, parallel rails fixed to said base and extending in the direction of movement of said top boards, a guide upon each of said top boards for each of said rails, said guides comprising an angle member one face of which rides upon the top of said rail and the other face of which extends along the side of said rail, said guides arranged in pairs whereby the top faces of two guides will overlie a single rail, the side faces thereof 85 lying on either side of said rail to prevent lateral movement of said top boards, and rollers on the top of said rails to form a bearing for said top faces of the guides, and rollers on the sides of said rails to provide a bearing for the side faces of said guides, means comprising a shaft fixed to said base and bearing a drum, pulleys upon said base to endless cable members oppositely wound about said drum and passing over said pulleys, each of said cables attached to and controlling the movement of one of said top boards. 90

4. In an extension table, a base, and top boards 105. slidable over said base toward and away from each other, and mechanical means for controlling the movements of said top board comprising a shaft rotatably attached to said base and bearing a drum, an endless cable for each of said top boards and attached thereto, each of said cables oppositely wound around said drum and passing over pulleys at the ends of said base whereby when said shaft is rotated in one direction said top boards will be moved toward each other, and when said shaft is moved in the other direction said top boards will be moved away from each other, and means for rotating said shaft comprising a detachable handle. 110
